(57) **CLAIM**

The ornamental design for a vehicle instrument cluster, as shown and described.

DESCRIPTION

FIG. 1 is a perspective view of a vehicle instrument cluster showing my new design; and,

FIG. 2 is a front view thereof.

The heavy broken lines shown in the drawings represent the boundary of the claimed design and form no part of the claimed design. All other broken lines represent portions of the vehicle instrument cluster that form no part of the claimed design.
